RETRACTABLE BALL PEN LATCH MEANS

Herbert W. Sams, Atlanta, Ga., assignor to Scripto, Inc.

Application January 26, 1954, Serial No. 406,159

3 Claims. (Cl. 120—42.03)

This invention relates generally to retractable ball pens in which a ball point and reservoir unit is retractably arranged so that it may alternatively be withdrawn within the pen barrel when not in use or projected from the barrel for writing, and more particularly, to an improved latch means for holding the ball point unit at projected position and releasing it for retraction as desired.

Generally characterized, the latch means of the present invention comprises a plunger member arranged to project rearwardly from the pen barrel and slidably disposed at the rear barrel end for depression inwardly thereof, a pocket clip mounted on the pen barrel and having a rearwardly projecting latch portion biased laterally for releasably engaging and holding the plunger member when depressed, and means within the pen barrel yieldably biasing the plunger member for movement rearwardly when not engaged by the pocket clip latch portion. By this arrangement, the latching action is accomplished exteriorly of the pen barrel so as to avoid obstruction of the pen barrel interiorly by the latch mechanism and thereby allow a ball point and reservoir unit extending throughout the barrel length to be housed therein with a resulting substantially greater capacity in the unit.

The present invention is described in further detail below in connection with the accompanying drawings, in which:

Fig. 1 is an elevation of a retractable ball pen incorporating a latch means arranged according to the present invention, with the latch means shown in retracted position;

Fig. 2 is a vertical section corresponding to Fig. 1, but showing the latch means latched forwardly to hold the ball point and reservoir unit at projected position;

Fig. 3 is an enlarged plan view corresponding to Fig. 1; and

Fig. 4 is an enlarged fragmentary vertical section of the upper portion of the retractable ball pen shown in Fig. 1.

In the embodiment of the present invention shown in the drawings, the retractable ball pen illustrated comprises a barrel housing formed by a front barrel portion 10 and a rear barrel portion 12 assembled at a threaded connection 14 to house therein a ball point and reservoir unit constituted by an ink reservoir tube 16 fitted at its forward end with a ball point element 18. The ink reservoir tube 16 may advantageously be formed of a compressible plastic material and the ball point element 18 arranged to bottom at projected position in the writing tip of the front barrel portion 12, comparably to the disclosure in copending application Serial No. 386,946, filed October 19, 1953, now Patent Number 2,778,337. The use of a plastic ink tube 16 further facilitates its effective gripping by the latch means of the present invention in the manner noted further below.

Projecting rearwardly from the rear barrel portion 12 is a plunger member 20 which is slidably disposed at the

2

5 rear end of barrel portion 12 for depression inwardly thereof. The forward end of plunger member 20 is formed with an outwardly extending flange 22 forming an abutment surface in opposed relation to an inwardly facing shoulder 24 provided in the rear barrel portion 20 to confine the plunger member 20 at the projected position shown in Fig. 1. The plunger member flange 22 also serves to cooperate with a bias spring 26 bearing against the forward face thereof from a mounting in the 10 rear barrel portion 12 at an internal ridge 28, and by which the plunger member 20 is biased to assume normally the fully projected Fig. 1 position.

A pocket clip 30 is also mounted on the rear barrel portion 12 intermediately of its length as indicated at 15 32 with a latch arm portion 34 extending rearwardly therefrom to overlie the rear end of rear barrel portion 12, with a clearance aperture 36 provided therein so as to allow projection of the plunger member 20 as seen in Fig. 1. This pocket clip latch arm portion 34 is laterally biased (to the right as seen in the drawings), so that upon depression of the plunger member 20 it will shift to engage the rear end of the depressed plunger member 20 and thereby latch plunger member 20 together with ink reservoir tube and ball point element 18 at projected 20 position.

In order to facilitate this latching engagement of the pocket clip latch arm portion 34 with the plunger member 20, the plunger member 20 is advantageously shouldered inwardly adjacent its rear end as at 38, and formed 25 beyond this shoulder 38 with a rounded tip extension of reduced diameter as at 40, to provide a latching seat at the shoulder 38 on the plunger member 20. Release of the plunger member 20 for return to retracted or fully projected position under the force of bias spring 26 is 30 accomplished simply by pressing laterally (to the left as seen in the drawings) on the pocket clip latch arm portion 34 to align the aperture 36 with the longitudinal axis of the plunger member 20.

Because the plunger member 20 is engaged exteriorly 40 by the pocket clip latch arm portion 34, it may be formed as a tubular cap, to receive therein and grip for movement therewith the rear end of ink reservoir tube 16, with the rear latching shoulder 38 of the plunger member 20 serving internally as a bottoming shoulder for the ink tube 16 45 and thereby permitting the entire extent of the forward and rear barrel portions 10 and 12 to be used as a housing for the ink tube 16 so that the allowable extent of ink tube 16 is substantially increased over the usual arrangement in retractable ball pens.

The present invention has been described in detail above for purposes of illustration only and is not intended to be limited by this description or otherwise except as defined in the appended claims.

I claim:

55 1. In a retractable ball pen, the combination with a barrel housing of a pocket clip attached intermediately of its length to said barrel housing with a flexible clip portion extending forwardly from said attachment and a flexible latch arm portion extending rearwardly therefrom, the extending end of said latch arm portion being formed laterally to overlie the rear end of said barrel housing and having an aperture therein alignable at the longitudinal axis of said barrel housing, and a plunger 60 projecting rearwardly from said barrel housing through said latch arm portion aperture and slidably disposed within said barrel housing for depression inwardly along the longitudinal axis thereof, said plunger being yieldably biased rearwardly with respect to said barrel housing and having a shoulder at its rear end with a tip portion of reduced diameter extending rearwardly from said shoulder, and said latch arm portion being biased later-

ally for displacing said aperture and thereby releasably engaging the plunger shoulder and retaining said plunger when depressed.

2. A retractable ball pen comprising a barrel housing formed with an inwardly facing annular shoulder adjacent the rear end thereof, a rearwardly projecting plunger slidably disposed at the rear end of said barrel housing for depression inwardly thereof and formed with an outwardly extending annular flange disposed forwardly of said barrel housing shoulder in opposed relation thereto, means carried interiorly by said barrel housing for yieldably biasing said plunger rearwardly with the flange thereof abutting said barrel housing shoulder, said plunger being further formed adjacent its rearwardly projecting end with an inwardly stepped shoulder and a tip portion of reduced diameter extending therebeyond, and a pocket clip mounted intermediately of its length exteriorly on said barrel housing with a flexible latch arm portion extending rearwardly from said mounting, the extending end of said latch arm portion being formed laterally to overlie the rear end of said barrel housing and having a clearance aperture therein allowing rearward projection of said plunger therethrough, and said latch arm portion being laterally biased for shifting against said plunger shoulder on the side thereof that is opposite the mounting of said pocket clip and thereby releasably engaging said plunger shoulder upon depression of said plunger to dispose the tip portion thereof at said aperture.

3. In a retractable ball pen, the combination with a barrel housing of a clip attached intermediately of its length to said barrel housing with a flexible clip portion

extending forwardly from said attachment and a flexible latch arm portion extending rearwardly therefrom, the extending end of said latch arm portion being formed laterally to overlie the rear end of said barrel housing and having an aperture therein alignable at the longitudinal axis of said barrel housing, and a plunger projecting rearwardly from said barrel housing through said latch arm portion aperture and slidably disposed within said barrel housing for depression inwardly along the longitudinal axis thereof, said plunger being yieldably biased rearwardly with respect to said barrel housing and having a rearwardly facing shoulder arranged thereon for engaging said latch arm portion on the side thereof opposite the mounting of said pocket clip, and said latch arm portion being laterally biased for shifting against said plunger shoulder and releasably engaging said plunger when depressed.
